(57) **CLAIM**

The ornamental design for a portable sauna, as shown and described.

DESCRIPTION

FIG. 1 is a front, right, top perspective view of a portable sauna, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2; and,

FIG. 12 is an enlarged view of detail 12 in FIG. 3.

The dashed broken lines in the figures are for the purposes of illustrating portions of the portable sauna and form no part of the claimed design.

The dash-dot-dash broken lines define the bounds of the enlargements and form no part of the claimed design.

1 Claim, 10 Drawing Sheets
